(57) **CLAIM**

The ornamental design for a golf club head, as shown and described.

DESCRIPTION

FIG. 1 is a sole, heel side perspective view of a new design of a golf club head;

FIG. 2 is a heel side view thereof;

FIG. 3 is a back view thereof; and,

FIG. 4 is a bottom view thereof.

The portion of the club head shown in phantom does not form any portion of the present invention.
